INDICATOR BOARD

Oliver R. Hartzell, San Rafael, Calif.

Application December 10, 1934, Serial No. 756,817

5 Claims. (Cl. 40—97)

This invention relates to an indicator and particularly to a score indicator or score board.

The primary object of the invention is to provide a score board which by an easily manipulated or remote controlled movement shows a series of numerals or indicia indicating the score in a game by successively uncovering the appropriate numerals or signs of said series.

Another object of the invention is to provide a score indicator in which a series of separate marked boards or flaps are successively rendered visible to indicate the score, and which after each adjustment also renders visible the back face of one of said boards or flaps exposing to view the markings on the backs of said boards or flaps.

Another object of this invention is to provide a score indicator which is highly useful and simple in construction. Convenience of arrangement, lightness and comparative inexpense of manufacture are further objects which have been borne in mind in the production and development of the invention.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawing.

The invention is clearly illustrated in the accompanying drawing, wherein:

Figure 1 is a front view of my device.

Figure 2 is a side view of my device partly in section.

Figure 3 is a fragmental sectional view of the conveyor and its edge of the device shown in Figure 1.

Figure 4 is a fragmental front view of another embodiment of my device, and

Figure 5 is a fragmental side view of said second embodiment of my device.

In carrying out my invention I make use of a preferably vertical frame having sides 5, connected by a base 6 at their lower ends, and by a top 7 at their upper ends. The top 7 is adapted to be hung on a hook on a wall not shown, but, if desirable, the frame may be set on its base 6.

In the frame between the sides 5 is disposed a suitable endless conveyor 8. The conveyor 8 may be a double or single chain or a belt conveyor, but for purposes of illustration I show an endless belt conveyor made of canvas or the like which has reinforcing bands 9 around the edges thereof. Each band 9 is made of flexible metal

or leather and has suitably spaced eyelets 11 placed thereinto. A transverse shaft 12 journaled in the sides 5 is extended near the lower turn of the conveyor 8 and carries sprockets 13 the teeth or pins of which latter engage the eyelets 11 successively thereby imparting movement to the conveyor 8 as the shaft 12 is turned.

A guide roller 14 of comparatively small diameter supports and guides the upper turn of the conveyor 8 so as to cause a comparatively sharp turn at the top. For score indication the conveyor is preferably so moved that the front of the conveyor moves upwardly. The point where the conveyor 8 turns from the front of the device to the rear will be hereinafter referred to as the leading end of the conveyor, and the point where the conveyor turns from the back toward the front of the device will be referred to as the trailing end of the conveyor.

On the conveyor 8 are secured a plurality of 20 separate boards or flaps 16. Each flap 16 is made of a flat board of suitable material such as cardboard, wood or the like. Each flap 16 is hung by its upper leading edge in any suitable manner such as by means of a leather hinge 17 sewed onto the conveyor belt 8. On the outside face of each flap 16, at the front of the conveyor 8, are suitable markings for the score, such as numerals, denoted by 18, in consecutive order on the series of said flaps. In the herein illustration the score indicator is particularly designed for use in connection with basket ball games and there may be about thirty or forty flaps with numerals from "1" to "30" or "40". There are two similar units or a double unit used to indicate the scores of each team. On the underside or normally hidden face of each flap 16 are markings or designs 19, preferably for advertising purposes.

The leading edges of the flaps 16 are so spaced, and the narrow turn of the leading end of the conveyor 8 is so pointed that as one flap 16 reaches near the top on the front of the conveyor 8, the next preceding flap 16 is turned and inverted at the top of the rear of the conveyor 8 as shown. Thus the uppermost flap 16 at the front is uncovered to expose to view a numeral thereon, and at the same time the underside or rear face of the next proceeding flap 16 is rendered visible as extended beyond and above the leading end of the conveyor 8 so as to expose to view the markings or advertisement 19. By suitably turning the shaft 12 the numerals and advertisements in view are consecutively changed.

The front of the frame has a cover 21 thereon to cover the front of the device except the uppermost flap 16 which latter is above the top edge of the cover 21. It is to be noted that the trailing ends of the flaps 16 in the front overlie the leading edges of the respective following flaps 16,

hence the flaps 16 are also covered partly by the respective preceding flaps 16, and a shorter conveyor may carry a larger number of flaps 16, rendering the device compact.

5. Along the rear of the conveyor 8 is a guide 22 to prevent the flaps 16 to fall or lean backward in case the hinge 17 is flexible. The flaps 16 drop in line again before they are turned to the front at the trailing end of the conveyor 8.
10. In operation, whether the conveyor 8 is held vertically or at any other angle the score indicator is adjusted in the same manner. Namely, the shaft 12 is turned until a desired numeral appears at the leading end of the conveyor 8, and at the same time the rear face of another flap 16 is visible beyond the leading end of said conveyor. The sprockets 13 and the eyelets 11 are so spaced that a predetermined turn of the sprockets 13 moves the uppermost flap 16 around 15 the leading end and from the front to the rear of the conveyor to render the rear face of the flap 16 visible. The shaft 2 may be manipulated by a crank 23 directly. It may be operated by remote control in any suitable manner such as 20 mechanically or electrically. A sprocket or sheave 24 on the shaft 12 is turned by a chain or wire 26 from a remote point. Ratchet mechanisms or electro-magnetic mechanisms may be connected to the shaft 12 for turning it. In all 25 instances the authentic score can be readily shown and controlled by the referee or official without leaving his position.

The embodiment illustrated in Figures 4 and 5 shows the use of plates or flap 28, made of thin metal. The upper edge of each plate 28 is secured to a block 29 of a chain conveyor 31 by means of a screw bolt 32 and washers 33, one washer on each side or face of each plate 28. Either a double chain conveyor may be 35 used at the opposite vertical edges of the series of plates 28, or a single chain at the middle of the plates 28 as shown. The chain is made out of the usual blocks 29 and links 34 connecting the adjacent blocks. In the herein illustration 40 every second block 29 is utilized to carry a plate 28. The lower sprocket, not shown is larger than the top sprocket 35 which latter is suitably constructed to hold a block 29 in front and another in the rear in substantially parallel positions so 45 as to expose to view at the same time the front face of the front uppermost plate 28 and the rear face of the rear uppermost plate 28. The chain conveyor is so arranged that it slants downwardly and rearwardly allowing the plates 28 in 50 the front of the device to freely overhang the respective underlying plates 28. This type of conveyor is preferably driven for adjustment at the upper sprocket 35.

The flaps 16 and the plates 28 may be marked 55 to suit the particular use of the device. For instance the indicia may take the form of lines of a song for a song chart, as indicated at 36 in Figures 4 and 5, or it may be in any other form required for a form chart or the like.

65. Having thus described my invention what I claim and desire to secure by Letters Patent is:

1. In a score board, a frame, a substantially vertical endless, upwardly converging conveyor on the frame, a series of indicating flaps on said conveyor the leading edge of each flap being connected to the conveyor, the leading edges of

adjacent flaps being spaced at a distance substantially equal to one-half of the circumference of the upper turn of the conveyor so that each flap is held inverted and visible beyond the end of the conveyor when it is turned from the front to the rear of the conveyor, the trailing edge of each preceding flap overlapping the next successive flap of the series when lying alongside the conveyor.

5. In a score board the combination with an endless conveyor adapted to be moved intermittently in a frame, of a series of flaps hung on the conveyor by their respective leading edges and being so spaced that when one flap is at the leading end of the conveyor the next preceding flap 15 is extended from the rear and beyond said end of the conveyor in inverted position thereby to successively expose to view both faces of each flap, the trailing edge of one flap overlying the next flap when linearly advanced by the conveyor, said 20 conveyor being held in a substantially vertical position with its leading end at the top, and the turn of the conveyor at its upper end being such that substantially one half of the circumference of the turn is equal to the spacing between two 25 adjacent flaps on the conveyor, and said upper turn being of smaller diameter than that of the lower turn of the conveyor.

3. In combination a chain conveyor, a plurality of plates connected at their respective leading 30 ends to spaced elements of said conveyor, said plates and conveyor elements being so spaced that said spacing is substantially equal to one half of the circumference of the leading turn of the conveyor and two plates are held parallel at 35 said turn, one at the front, another at the rear to successively expose to view the opposite faces of each plate as the conveyor is turned, each plate having markings on both faces thereof.

4. In combination a chain conveyor, a plurality of plates secured at their respective leading ends at spaced elements of said conveyor, the distance between the front and rear branch of the conveyor at the trailing end of the conveyor being larger than at the leading end thereof, said 45 plates and conveyor elements being so spaced that two plates are held parallel at the top, one at the front, another at the rear to successively expose to view the opposite faces of each plate as the conveyor is turned, each plate having markings on both faces thereof, said conveyor being inclined downwardly and rearwardly so that the plates on the front of the conveyor overhang by gravity the preceding plates overlapping the respective following plates.

5. In a display device of the character described a frame, a substantially vertical, endless conveyor on the frame, the upper turn of the conveyor being smaller than its lower turn so as to cause the rear and front sides of the conveyor to upwardly converge, a plurality of overlapping flaps connected to said conveyor by their respective leading edges so as to turn into inverted position at the rear of the upper turn of the conveyor, the leading edges of adjacent flaps being spaced on the conveyor at a distance substantially equal to one half of the circumference of the upper turn of the conveyor, and a mechanism connected to said conveyor whereby intermittent movement can be imparted to said conveyor.

70 OLIVER R. HARTZELL.
